UNITED STATES PATENT OFFICE.

RICHARD DRAKE, OF RACINE, WISCONSIN.

TRAY HOLDER OR SUPPORT.

1,202,816.

Specification of Letters Patent.

Patented Oct. 31, 1916.

Application filed May 24, 1915. Serial No. 30,130.

To all whom it may concern:

Be it known that I, RICHARD DRAKE, a citizen of the United States, residing at Racine, in the county of Racine and State 5 of Wisconsin, have invented new and useful Improvements in Tray Holders or Supports, of which the following is a specification.

This invention relates to a tray holder or support, and one of its objects is to provide 10 a device for supporting an ash receptacle or other kind of tray, whereby the tray may be supported in an upright position upon a horizontal surface or clamped to the edge of a table, chair or other article.

15 A further object of the invention is to provide a device of the character described which is adapted for many and various uses in supporting or clamping trays or receptacles of different kinds, and which may be 20 employed without injury to article of furniture to which it may be applied.

25 A still further object of the invention is to provide an article of the character described which, when employed as a smokers' article, may serve as a support or clamp for an ash tray as well as a match holder.

30 The invention consists of the features of construction, combination and arrangement of parts herein fully described and claimed, reference being had to the accompanying drawing in which:—

35 Figure 1 is a side elevation of the device as arranged to rest upon a table or other horizontal surface. Fig. 2 is a view showing 40 the device as clamped to the edge of a table or other surface. Fig. 3 is an end elevation. Fig. 4 is a vertical longitudinal section.

45 In carrying my invention into practice, I provide a combined supporting and clamping device 1 which is formed of a strip of spring metal, which strip is bent to form an upper straight supporting arm 2 and a lower curved supporting arm 3, the arms 2 and 3 being united at one end by a spring 50 loop 4, whereby the opposite ends 5 and 6 of the respective arms are adapted to serve as spring clamping members. The arms 2 may support a tray or receptacle 7 of any suitable character. In the present instance 55 I have shown a tray of the type adapted for use as an ash receiver and carrying a cigar supporting shelf 8, but the receptacle may be employed for holding bonbons, manicure or sewing articles, or other articles designed 60 for use for any intended purpose. When the

device is employed in a smokers' article of the character defined, or for any analogous purpose where matches are used, I may provide upon the portion 4 of the device a spring clip 9 of the kind commonly employed for holding a box of safety matches. 60

Secured to and depending from the jaw 6 or free end of the arm 3 are supporting legs 10 or their equivalent, which are carried by a cross bar 11 brazed or soldered to the arm 65 3, and which forms the bearing surface of the jaw 5. This surface and the coöperating portion of the jaw 5 may be provided with layers of a soft material 12, such as felt, by which injury to the portions of furniture or 70 other articles gripped between the jaws may be prevented.

75 It will be observed that the lower end of the clip 9 terminates in the plane of the base of the curved supporting arm 3 and the lower ends of the legs 10, whereby said clip may serve as an additional leg or support when occasion requires.

80 As shown in Fig. 1, the device may be rested upon a table or other horizontal support, the lower portion of the loop 4 and the legs 10, which terminate in the same horizontal plane, providing effective supporting members at the opposite ends of the device by means of which it may be stably 85 supported. The device may also be clamped to the projecting edge of a table top, or the seat or arm of a chair, as shown in Fig. 2, so that it may be applied in a variety of positions and to various articles where it 90 may be conveniently used.

95 As stated, the mode of use of the device, or the purpose for which it is intended, may be varied; and hence I do not limit the invention in this particular.

I claim:—

100 A tray holder or support comprising a spring strip bent into looped form to provide an upper, straight horizontally extending arm, a lower compoundly curved arm extending at an angle toward one of the ends of the horizontal arm, and a looped spring portion connecting said lower arm with the other end of said horizontal arm, the free ends of the respective arms being 105 provided with clamping surfaces to form co-acting jaws, the curved arm having a curved portion of major depth arranged to form a supporting surface, a supporting member carried by the bight portion of the loop and 110

depending into the plane of said supporting portion of the lower arm, and a forked supporting leg pivotally connected with the free end of the lower arm and adapted to be 5 turned down to supporting position in the plane of said supporting surface and supporting member.

In testimony whereof I affix my signature in presence of two witnesses.

RICHARD DRAKE.
